E. H. BRYANT.
LEVER LOCK FOR AUTOMOBILES.
APPLICATION FILED MAR. 1, 1913.

Patented June 23, 1914.

Witnesses:

Yours England,
David P. Reedson.

Inventor,
Carroll B. Bryant.

UNITED STATES PATENT OFFICE.

EARNEST H. BRYANT, OF CLEVELAND, OHIO, ASSIGNOR TO THE E. H. BRYANT COMPANY, OF CLEVELAND, OHIO, A CORPORATION OF OHIO.

LEVER-LOCK FOR AUTOMOBILES.

1,101,117.

Specification of Letters Patent. Patented June 23, 1914.

Application filed March 1, 1913. Serial No. 751,431.

To all whom it may concern:

Be it known that I, EARNEST H. BRYANT, a citizen of the United States, residing at Cleveland, in the county of Cuyahoga and State of Ohio, have invented certain new and useful Improvements in Lever-Locks for Automobiles, of which the following is a specification.

This invention appertains to lever locks for automobiles or motor vehicles, and is especially an improvement or refinement of the lock disclosed in my copending application, Serial No. 642,990, filed August 8, 1911.

This invention contemplates the provision of a novel and improved lock of the character indicated, which may be attached to the hand or gear shift levers of various machines and which shall be operable to engage the speed gate, segment or quadrant in which the lever works, so as to lock the lever in neutral position and to thereby prevent the shifting or intermeshing of the transmission or speed change gears.

It is also the object of the invention to provide a lock of the type suggested, which shall embody a spring-pressed speed gate engaging member that may be readily pressed, pushed or forced into depressed or speed gate-engaging position, and which shall embody key-controlled means for retaining the gate-engaging member in operative or locking position, so that unwarranted releasing or liberating of the lever by those maliciously or mischievously inclined is prevented, and so that the introduction or insertion of a proper key will permit the gate-engaging member to release the speed gate and return to normal or initial position due to the tension of its spring.

Another object of the present invention is to provide a lever lock constituting a novel, compact and improved assemblage of parts to increase the efficiency, utility and other characteristics generally, and to provide a highly desirable, meritorious and serviceable lock.

A further object of the invention is to provide a lock of the nature specified which shall be applicable to various levers in such a manner as not to be capable of ready displacement or distortion by malicious persons or due to the conditions to which the lock is otherwise subjected in use.

A still further object is to provide a novel

concealed spring for normally raising the speed-gate engaging member.

It is also the object of the invention to provide a novel closure for the lock which shall conceal and render inaccessible the interior working parts of the lock when it is engaged to the casing of the lock, but which shall permit of the ready assemblage of the parts prior to its engagement with the casing.

With the foregoing general objects outlined and with other objects in view, which will appear as the nature of the invention is better understood, the present invention resides in the construction, arrangement and combination of parts hereinafter described and claimed, it being understood this invention may be susceptible to various alterations and modifications within the scope of what is claimed without departing from the spirit of the invention and without sacrificing the benefits derived.

The invention has been illustrated in its preferred embodiment in the accompanying drawing, wherein:

Figure 1 is a perspective view of the lock as applied to a lever and showing the parts in position to dead-lock the lever. Fig. 2 is a vertical section of the lock. Figs. 3, 4 and 5 are sectional views taken on the respective lines 3—3, 4—4 and 5—5 of Fig. 2. Fig. 6 is a sectional detail.

In carrying out the present invention, reference being had to the drawing in detail, there is provided a case or body 6, which is attachable to the lever L which works in the speed gate G, it being understood that when the transmission is idle or at neutral, the lever will stand at such a position that it must be shifted laterally and then swung in order to operate the transmission gearing so as to connect the motor with the propelling wheels. It is to be understood, however, that the present lock may be applied to various levers and speed gates.

The case 6 has an opening 7 extending from one side to the other around the front, and terminating adjoining the back of the case, and a closure, cap or cover 8 is provided for the opening. The cap is U-shaped and the edges of the cap and opening are provided with the interengaging rabbets or grooves 9, which facilitate the positioning of the cap, as well as holding the cap rigid.

when slid to position. The ends of the cap are adapted to abut against the ends of the opening, as at 10, and it is to be noted that the opening 7 is completely closed and that 5 the cap is flush with the case. At the ends of the opening 7 the case is provided with the inturned or inwardly projecting ears or lugs 21, while the ends of the cap are provided with the complementary hooks or 10 catches 26. The hooks 26 are designed to snap or lock into engagement with the ears 21 when the cap is slid home, so as to prevent the subsequent removal of the cap. It is to be understood that the cap is not made 15 fast until the case has been properly applied to the lever, as will be described.

As a means for attaching the case to the lever, there has been provided the following essentials: The back of the case is provided 20 with a pair of outwardly projecting flanges 11, which are preferably tapered from their lower ends to their upper ends, and which are designed to straddle the sides of the lever, while the back of the case rests or 25 abuts against the edge of the lever. The back of the case is also provided with a transverse rib 12 between the flanges, which is designed to engage in a transverse notch or groove cut or filed in the edge of the lever. 30 Thus, the rib prevents the case from climbing or sliding on the lever, while the flanges resist any twisting or lateral strain applied to the case. A U-clip 13 embraces the lever and is provided with bolt or threaded 35 ends piercing the back of the case next outside the respective flanges. Nuts 14 are threaded onto the ends of the clip so as to clamp the back of the case tightly against the lever. Lock washers 15 are preferably 40 interposed between the nuts and the back of the case to prevent the retrograde movement or unscrewing of the nuts when tightened. It is to be observed that the opening 7 provides ready access into the case for tightening 45 the nuts.

A plunger 22 is slideable through the top and bottom of the case adjoining the back, and has a longitudinal bore 24 extending from its lower end to a point short of the 50 upper end, the upper end of the plunger being formed into a head or button for the engagement of the operator's finger to depress the plunger. To the lower end of the plunger there is secured the speed gate eng- 55 gaging member proper, which embodies a head 18 having a shank or tang threaded, welded, brazed, or otherwise permanently secured within the lower end of the plunger, as at 17, after the plunger has been inserted 60 through the case. The head 18 is adapted to normally seat against the lower end or bottom of the case, and is provided with an integral fork 19. The fork is offset so that its arms overlap or straddle the sides of the 65 lever, and the arms have the outer down-

wardly-tapered ribs or wedges 20. The butt ends of the arms are relatively wide, while the free ends are pointed.

The plunger 22 is provided with slots 27 in its sides and within the case, and through 70 which, a pin 23 is passed. The pin 23 is carried by a pair of fingers 16 projecting from the back of the case and between which the plunger fits. A coiled wire compression spring is disposed within the bore 24 and is seated between the pin 23 and the upper end of the plunger, so as to give an upward tension to the plunger. The spring 75 may be readily inserted into the plunger prior to the introduction of the plunger through the case, and the pin 23 may be readily inserted under the spring, as permitted by the opening 7. Thus, the spring is effectively concealed and still has a considerable latitude of play, and the pin will be concealed by the cap. The plunger is also formed with a series of ratchet teeth 28 along its forward side below the top of the case.

The case is provided with a socket 29 at 90 its front portion, the socket opening upwardly or through the top, and a key controlled mechanism 30 is seated in the said socket. This mechanism embodies a case or body fitting snugly in the socket 29 flush with the top of the case 6. The case 6 is further provided with a horizontal passage or slideway 31 directly below the socket, and which extends from the front to the plunger. The key-controlled mechanism 30 includes an upright barrel 32 designed to receive and be turned or rotated by a key, the lower end of the barrel projecting through the bottom of the socket and having an eccentric 33 depending therefrom within the slideway 31. 95 Within the slideway 31 there is disposed a latch bolt 34 which has its inner end beveled to engage the ratchet teeth 28 to hold the plunger in depressed position. The latch bolt has an upper notch or recess 35 in 100 which the eccentric 33 is engaged, so that the latch bolt may be retracted by the barrel. A coiled wire spring 36 is also disposed in the slideway 31 behind the latch bolt, and a pin 39 is engaged through the outer or forward end of the slideway, the spring 36 being seated between the pin 39 and the outer or forward end of the latch bolt to press the latch bolt into engagement with the plunger. The fingers 16 are connected to the inner or rear end of the slideway. It is evident that 105 the mechanism 30, latch bolt, spring 36 and pin 39 may be easily inserted into the case.

The key-controlled mechanism 30 may be adapted for any number of keys, that is, 115 various mechanisms 30 may be provided for various locks so that the several locks will require separate or distinct keys, and in order that one lock may not be opened by the holder of a key for another lock. 120

The key changes may thus be indefinite in number. To secure the case of the mechanism 30 in place, a pin or securing member 37 is engaged through one side of the socket 29 and takes into the said case, the pin being inclosed by the cap after the cap is applied. It is also desirable to provide a pivoted cap or cover 38 for the mechanism 30, in order to normally exclude dust and to conceal the barrel 32. This cover 38 may be readily swing into and out of position.

In use, the present lock may be quickly and easily applied to the lever, it only being necessary to file a small notch in the proper edge of the lever to receive the rib 12. The application of the lock to the lever does not unduly encumber the lever or injure or impair it in any way. The case is also so secured to the lever that undue strains will not tend to distort or break the lock, this being particularly true in connection with the fork straddling the lever so that its arms may wedge between the sides of the lever and gate when the plunger is depressed. After the case has been secured in position and the various parts placed in position, the cap may be secured to the case so as to prevent tampering with the working parts within the case. The lever may be readily locked by simply depressing the plunger until the fork properly engages within the speed gate, the latch bolt engaging the ratchet teeth 28 to prevent the plunger from rising until the barrel 32 is turned by the proper key inserted thereinto. The ratchet permits the fork to lock at various positions as is necessary with the various levers, and by turning the barrel, the latch bolt may be retracted so that the spring 25 will raise or release the fork with the plunger.

The many advantages and capabilities of the invention will be manifest from the foregoing.

45 What is claimed is:—

1. In a lever lock for automobiles, a case, a hollow plunger slidable therethrough and having a speed gate engaging member at one end, means within the case for locking the plunger, and a coiled wire spring housed within the plunger and seated between the plunger and case.

2. In a lever lock for automobiles, a case, a hollow plunger slidable therethrough and having a speed gate engaging member at one end, means within the case for locking the plunger, a member carried by the case and projecting into the plunger, and a coiled wire spring housed within the plunger and seated between the said member and the plunger.

3. In a lever lock for automobiles, a case, a hollow plunger slidable through the case and having speed gate engaging means at one end, the case having portions at the sides

of the plunger and the plunger having slots in its sides, a pin carried by the said portions and passing through the said slots, a coiled spring housed within the plunger and seated against the said pin, and means 70 within the case for locking the plunger.

4. In a lever lock for automobiles, a case having an opening extending from side to side, a hollow plunger slidable through the top and bottom of the case and having slots 75 in its sides within the case, the case having portions at the sides of the plunger, a pin engaged through the said portions and passing through the said slots, a coiled spring housed within the plunger and seated 80 against the said pin, a U-shaped cap for the opening in the case, and means for locking the plunger.

5. In a lever lock for automobiles, a case, a plunger slidable therethrough, the plunger 85 having a bore extending from one end to a point short of the other end and a slot within the case, a member carried by the case and projecting through the slot of the plunger, a coiled spring housed within the said bore 90 and seated between the latter end of the plunger and the said member, means within the case for locking the plunger, and a speed gate engaging member secured to the former end of the plunger. 95

6. In a lever lock for automobiles, a case having an opening in its side, a plunger slid- 100 able through the top and bottom of the case, the plunger having a bore extending from its lower end to a point short of the upper end and slots in its sides within the case, the case having portions at the sides of the plunger, a pin engaged through the said portions and passing through the said slots, a coiled wire spring housed within the said 105 bore and seated between the upper end of the plunger and the said pin, a speed gate en- gaging member having a shank secured within the lower end of the plunger, means within the case for locking the plunger, and 110 a closure for the said opening.

7. In a lever lock for automobiles, a case having a socket opening through its top and a slideway below the socket, a plunger slid- 115 able through the case and having speed gate engaging means at one end, a latch bolt slideable in the said slideway, key-controlled means disposed within the said socket for actuating the latch bolt, the bolt serving to lock the plunger, and means engaging 120 through one side of the socket within the case to secure the key controlled means within the socket.

8. In a lever lock for automobiles, a case having a socket opening through its top and 125 a slideway below the socket, a plunger slid- able through the case and having speed gate engaging means at one end, a spring-pressed latch bolt within the slideway to lock the plunger, key-controlled means including a 130

- case fitting in the socket and an upright barrel having its lower end operatively engaged to the latch bolt through the bottom of the socket, and means within the aforesaid 5 case engaging through one side of the socket to lock the last mentioned case within the socket.
9. In a lever lock for automobiles, a case having an upwardly opening socket adjoining the front, an opening extending from side to side around the front, and a slideway below the socket, a plunger slidable through the top and bottom of the case adjoining the back, a latch bolt slidable in the slideway 10 and engageable with the plunger, a spring fitting in the slideway behind the latch bolt, key-controlled means including a case fitting in the socket and a barrel having its lower end engaged to the latch bolt, securing 15 means engaged through the side of the socket and taking into the last mentioned case, and a U-shaped closure for the opening in the case.
10. In a lever lock for automobiles, a case 20 adapted to abut against a lever, the case having members to straddle the lever and a member therebetween to engage a notch in the lever, a clip for embracing the lever and terminally securable within the case, a plunger slidable through the case and having 25 speed gate engaging means at one end, and means disposed within the case for locking the plunger.
11. In a lever lock for automobiles, a case 30 adapted to abut against one edge of a lever, the case having a pair of flanges to over-lap the sides of the lever and a transverse rib between the flanges to engage a transverse 35 notch in the edge of the lever, a clip for embracing the lever, the ends of the clip piercing the case next outside the flanges and being secured within the case, a plunger slid- 40 able through the case and having speed gate engaging means at one end, and means within the case for locking the last mentioned 45 member.
12. In a lever lock for automobiles, a case 45 adapted to abut against a lever and having an opening extending from side to side around the front and terminating adjoining the back of the case, a clip for embracing the lever and having its ends piercing the back of the case, nuts threaded onto the ends of the clip to clamp the back of the case 50 against the lever, a plunger slidable through the top and bottom of the case and having speed gate engaging means at one end, means within the case for locking the plunger, and a U-shaped cap for the opening.
13. In a lever lock for automobiles, a case 55 having an opening extending from side to side around the front and terminating adjoining the back, a plunger slidable through the top and bottom of the case and having speed gate engaging means at one end, 60 means within the case for locking the plunger, and a U-shaped cap for the opening, the case having inwardly projecting ears at the ends of the opening and the ends of the cap 65 having hooks to snap over the ears.
- In testimony whereof I do hereby affix my signature in presence of two witnesses.
- EARNEST H. BRYANT.
